UNITED STATES PATENT OFFICE.

GUSTAVE E. FRANQUIST, OF ROCHESTER, NEW YORK, ASSIGNOR TO JAMES CUNNINGHAM, SON & COMPANY, OF ROCHESTER, NEW YORK, A CORPORATION OF NEW YORK.

FASTENING DEVICE.

Application filed February 26, 1921. Serial No. 448,028.

To all whom it may concern:

Be it known that I, GUSTAVE E. FRANQUIST, of Rochester, in the county of Monroe and State of New York, have invented certain new and useful Improvements in Fastening Devices; and I do hereby declare the following to be a full, clear, and exact description of the same, reference being had to the accompanying drawings, forming a part of this specification, and to the reference numerals marked thereon.

This invention has to do with fastening devices and relates more particularly to such as are adapted for fastening a closure, such, for example, as the motor hood of an automobile, one object of the invention being to provide a practical and convenient device of the above character having a single handle which serves not only for movement of the closure to and from closed position but also operates the fastening device, facilitating quick and convenient adjustment of the closure. Another object is to provide a device of the above character located inside the closure with the parts so constructed and arranged as to hold the latter securely against the body, together with means for automatically guiding the fastening device to and from engaged position. A further object is to provide in combination with the above an additional lock controlled fastening means preventing unauthorized opening of the hood. To these and other ends the invention consists in certain improvements and combinations of parts, all as will be herein-after more fully described, the novel features being pointed out in the claims at the end of the specification.

In the drawings:

Figure 1 is an external side elevation of a fastening device embodying the present invention.

Figures 2 and 3 are sectional elevations on the line 2^a—2^a of Figure 1 showing the parts in different positions.

Figure 4 is a sectional detail view on line 4^a—4^a of Figure 2.

Figure 5 is a similar view on the line 5^a—5^a of Figure 1.

Figure 6 is a similar view on the line 6^a—6^a of Figure 1.

Similar reference characters throughout the several views indicate the same parts.

The present embodiment of the invention

shows the adaptation of the same to the purpose of fastening an automobile hood to the body, but the invention is applicable, of course, to other uses, this embodiment being intended merely by way of illustration of the principles involved and a preferred practical application thereof. At 10 is indicated one of the longitudinal beams or other part of the automobile body, while 11 indicates a closure or motor hood portion, in the present instance of the type commonly pivotally supported at one or more points 12 for movement outwardly and upwardly to expose the motor. Secured on the body, as by means of bolts 13, is a catch member or frame 14 having a base flange 15 through which the bolts 13 pass. Extending from the base flange are upwardly extending spaced web members 16 supporting the cross member or catch 17. The latter is formed on its upper side with a camming surface 18 for a purpose presently to be explained, and on its under side with a latch securing surface 19. One of the web members 16 carries a projecting portion 20 having an angular part 21 extending parallel with the inside of the hood, for a purpose which will later appear.

The latch portion of the device preferably comprises an open frame 22, Figure 4, having at its upper end a support or post 23 projecting inwardly from the hood and provided with a threaded shank 24 extending exteriorly through an opening in the hood to receive a nut 25 securing the upper end of the frame firmly to the hood. The inner end of post 23 is bifurcated as at 26 to receive the upper end of a depending part or spindle 27 secured to the hood by a lock bolt 28 carried in the arms of the post. The lower end of spindle 27 is formed with a piston-like head 29 on which slides a part or a cylinder 30 having at its upper end a head 31 threadedly secured thereto and sliding on the spindle. Coiled about the spindle within the cylinder 30 between the head 31 of the latter and the end of the spindle is a compression spring 32 acting to urge the cylinder resiliently upward on the spindle away from the catch.

To guide the lower end of the cylinder 30 there is provided in sliding relation therewith a guide or collar 33 within a ring 34 carried by the lower end of frame 22 and secured therein as by means of a screw 35.

The lower end of the frame, as in the case of its upper end, is provided with a threaded shank 36 projecting externally through an opening in the hood to receive a nut 37 completing the secure attachment of the frame on the hood. To reinforce the latter adjacent the points of attachment of the frame there is provided a stiffening plate 38 embracing at its ends and extending between the shanks 24 and 36 of the frame.

10 The latch proper is carried by the lower end of cylinder 30, comprising a hook-like member 39, Figure 2, for engagement with the catch member 17, and it is to be noted 15 that the hook of the latch is formed with an external camming surface 40 and an internal camming surface 41 adapted to cooperate with the surface 18 of the catch so that when the latch is lowered for engagement with the catch it is thrown outwardly around the latter by the engagement of surfaces 40 and 18. Similarly for disengaging the latch the latter may be first depressed so that its surface 41, cooper- 20 ating with surface 18 of the catch, throws the latch hook outwardly clear of the catch so that it can then be swung outwardly and upwardly with the hood.

Carried by cylinder 30 and extending externally through an opening 42 in the hood is a handle 43 preferably in the form of a finger ring. With a fastening device of the present character provided at the ends of a hood portion, the handle means 43 not only serves to quickly and conveniently engage and disengage the latch in the manner described, but also to move the hood itself, thus facilitating the quick and convenient adjustment of the latter, and of course when the latch is engaged with the catch, spring 32 is stressed and draws the hood resiliently toward the body. Furthermore the location of the catch and latch within the hood provides for the application of the holding force of spring 32 to the hood in such a manner as to pull the latter tightly in an inward direction against the usual supporting surfaces on the body, thereby preventing any play or rattle of the parts. Fixed on and extending through the hood in any suitable manner adjacent the auxiliary catch part 21 is a lock mechanism 44, preferably of the key operated type, carrying at its rear end an auxiliary latch 45 adapted to be swung by operation of the lock to and from a position inside the auxiliary catch 21. When latch 45 is moved to position opposite or inside catch 21, the hood portion is securely locked against unauthorized opening.

In closing the hood section the latter is moved by grasping handle 43 which is pressed downwardly with the hood section and as the latter seats on the supporting

surfaces of the body the latch is moved downwardly, stressing spring 32 so that its camming surface 40 engages surface 18 of the catch and throws the latch hook around the catch for convenient engagement therewith, and such engagement draws the section inwardly toward the body and holds it securely against rattling. In opening the hood handle 43 is first pressed downwardly so that its camming surface 41, engaging surface 18 of the catch, throws the latch hook outwardly clear of the catch so that the hood may then be raised. The same catch part serves also in combination with the locking means to prevent opening of the hood except by use of a corresponding key. In addition to the advantages of the construction and arrangement already pointed out, the parts are located out of view within the hood so as to be afforded protection by the latter, and this arrangement preserves the desired simplicity of line in the structure and materially enhances its appearance.

I claim as my invention:

1. A fastening device for securing the motor hood of an automobile to the body thereof comprising a support projecting inwardly of the hood, a guide projecting inwardly of the hood in spaced relation with said support, a pair of telescopically extensible parts one of which is fixed at one end to said support and the other part slidably guided by said first part and by said guide for rectilinear extension and retraction, a spring resisting extension of said other part, a catch on said automobile body, a latch on said other part, and a handle on the latter projecting exteriorly through a slot in the hood.

2. A fastening device for securing the motor hood of an automobile to the body thereof comprising a post projecting inwardly of the hood, a guide projecting inwardly of the hood in spaced relation with the post, a telescopically extensible spindle and housing one of which parts is immovably fixed at one end to said post and the other of which is slidable rectilinearly on the first and on said guide, a compression spring in said housing connected at one end with the latter and at the other with said spindle for resisting said extending movement, a catch on the automobile body, a latch on the movable one of said extensible parts, and a handle on the latter projecting through a slot in the hood.

3. A fastening device for securing the motor hood of an automobile to the body thereof comprising a support projecting inwardly of the hood, a guide projecting inwardly of the hood in spaced relation with said support, a spindle fixed at one end to said support, a cylinder having a rectilinear extending movement on said spindle and

guide, a compression spring in the cylinder between the latter and the spindle for resisting extension of the cylinder, a handle projecting exteriorly from the cylinder 5 through a slot in the hood, a catch on the automobile body and a cooperating latch on the cylinder.

4. A fastening device for securing the motor hood of an automobile to the body 10 thereof comprising a support projecting inwardly of the hood, a substantially vertical guide depending from said support, a second guide on the hood spaced from the first, a catch on the automobile body, a part provided with a latch and having a rectilinear 15 extending movement on said guides to carry the latch toward and from the catch, a spring for retracting the latch, cooperating camming means on the catch and latch for 20 throwing the latter upon downward movement clear of the catch, and a handle on

said movable latch part projecting externally through a slot in the hood.

5. A fastening device for securing the motor hood of an automobile to the body 25 thereof comprising a frame secured on the inner side of the hood having adjacent its top an inwardly extending post and adjacent its bottom an inwardly extending guide collar, a spindle fixed to and depending from 30 said post, a cylindrical housing slidable on said spindle and in said collar, a compression spring in the housing connected with the latter and with said spindle to resist extension of said housing, a catch on said automobile body, a latch on said housing, said catch and latch having camming means for 35 throwing the latter clear of the catch upon downward movement, and a handle on said housing projecting through a slot in said 40 hood.

GUSTAVE E. FRANQUIST.
